UNITED STATES PATENT OFFICE.

BENJAMIN F. MIESSNER, OF SOUTH ORANGE, NEW JERSEY, ASSIGNOR TO WIRED RADIO, INC., OF NEW YORK, N. Y., A CORPORATION OF DELAWARE.

MICROPHONE.

Application filed May 14, 1925. Serial No. 30,164.

This invention has to do with telephonic microphones and relates more particularly to microphone pickup devices especially designed for radio and wired radio broadcast purposes.

It is the object of this invention to provide a microphone pickup which is exceedingly sensitive and approximately equally sensitive to sound waves propagated from all sides. A microphone pickup having these characteristics is especially desirable for use in broadcasting orchestral and other musical group performances, where it is necessary or convenient to place the pickup in the center of a group of musicians or to so place the musicians that the sound waves from the various instruments would not all be conveyed in one or two general directions to the pickup.

Microphone pickups of the kind commonly used, heretofore, are very much more sensitive to sound waves propagated directly against the diaphragm, or diaphragms, than to those propagated along planes parallel and approximately parallel to the plane of the diaphragm. On this account the best results are not attainable with such pickups in broadcasting the performances of large symphony orchestras and choirs.

A microphone pickup constructed in accordance with the preferred embodiment of the present invention is illustrated in the accompanying drawings and consists of a block or sheet of sponge rubber or other substance having substantially equal resiliency and damping characteristics. An aperture is formed extending through the sheet of sponge rubber and is enclosed at each end by means of exceedingly light, but rigid, discs or diaphragms preferably of mica and each provided with a very thin coating of platinum or other suitable foil on the sides adjacent the sponge rubber sheet. The chamber formed in the sponge rubber sheet by the discs or diaphragm is preferably filled with granular carbon which contacts with coatings of foil and across which the microphone current flows. The combination of elements thus brought together may be and is preferably of very light weight and is almost equally sensitive to sound waves from all directions.

In the accompanying drawing,

Fig. 1 is an elevational view of a micro-

phone pickup, in accordance with this invention and of the preferred form, and,

Fig. 2 is a longitudinal cross-section thereof.

The microphone pickup illustrated in the drawing, representative of the preferred embodiment of the invention, comprises a molded slab or sheet of sponge rubber 1, which may be about one and one-quarter inches long, one inch wide and one-eighth inch thick. An aperture 2 about one-half inch in diameter may be formed in the process of molding, or may be cut through the sheet of sponge rubber. A pair of discs or diaphragms, each comprising a relatively rigid sheet of mica, 3 and 4, respectively, and a thin coating of platinum or other suitable foil, 5 and 6, are secured to either side of the sponge rubber sheet 1 and preferably cemented thereto. The platinum foil is also preferably cemented to the mica discs. The chamber thus formed between the two platinum coated discs is partly filled with granular carbon 7. A pair of lead-in conductors 8 and 9 are connected respectively to the two platinum foil coatings and may, for convenience, be imbedded in the sponge rubber as indicated in Fig. 2.

The principle of operation of this microphone pickup is not unlike that of any other carbon microphone, except that due to the resiliency of the sponge rubber sheet 1 and the small mass of the discs or diaphragms, the device is found to be extremely sensitive and almost equally sensitive to sound waves propagated from all directions.

It is believed that the compression and rarefaction of the air caused by sound waves effects edge-wise compression and extension of the sponge rubber sheet, thereby varying the pressure of the carbon granules.

The present invention is amenable to considerable modification within its scope and spirit and should not be construed as limited except as indicated by the appended claims.

What is claimed is:

1. A microphone comprising a member of highly resilient substance, forming a sound collecting surface having an aperture therein adjacent one edge of said substance, a pair of light, rigid discs attached respectively to opposite sides of said member and forming closures for said aperture, conducting wires leading from each of said disks through said

- substance and forming suspension means for freely supporting said substance at a point adjacent the opposite edge thereof and granular microphonic material within the chamber formed by said aperture and said discs whereby sound vibrations incident upon said member impart corresponding compressional forces to said granular microphonic material within said chamber.
- 5 10 2. A microphone comprising a sponge rubber member forming a sound collecting surface having an aperture extending therethrough and unequally spaced from opposite edges of said member, a pair of discs secured to opposite sides of said member and forming closures for said aperture, said discs each comprising a relatively rigid sheet of mica and metallic foil coatings secured to said discs respectively, said coatings being adjacent said aperture and wire members connected to each of said metallic foil coatings and extending through said sponge rubber member and forming suspension means for freely suspending said microphone and 15 20 25 granular carbon partially filling the chamber formed by said aperture and said discs, said granular carbon contacting with said metallic foil coating whereby sound vibrations incident upon said member operate to produce corresponding compressional forces in said granular carbon in said chamber.
3. A microphone comprising a sheet of sponge rubber having an aperture therethrough, a pair of mica discs secured respectively to opposite sides of said sheet, said discs forming closures for ends of said aperture, respectively, a platinum foil coating on each of said discs, said coatings being adjacent said aperture, the chamber formed by said discs and aperture being partially filled with granular carbon, and lead-in conductors connected respectively to said platinum foil coatings, said sheet of sponge rubber forming a surface against which sound vibrations directly impinge for imparting corresponding compressional forces to said chamber of granular carbon.
- 35 40 45

In testimony whereof I affix my signature.

BENJAMIN F. MIESSNER.
